tion of Delaware

Application May 17, 1938, Serial No. 208,410

3 Claims. (Cl. 178—44)

The present invention relates to impedance inversion both with and without a change of sign. In what follows the term impedance inversion is used to denote the production of an impedance which is proportional to the reciprocal of a given impedance.

The object of the invention is to provide means for inverting any impedance, with or without change of sign, and coincidentally independently controlling the magnitude of the inverted impedance and the relative amounts of power flowing into the original impedance element and the inverse impedance derived therefrom.

Impedance inverters have been used in the past of which the well known quarter wave length transmission line is an example. When the output terminals of such a line are connected to an arbitrary impedance the impedance measured at the input terminals of the line is found to be the inverse of the impedance connected to the output terminals; specifically, the input impedance is equal to the square of the characteristic impedance of the line divided by the output impedance. This method of impedance inversion, as well as similar arrangements involving lumped reactance elements, is limited in its usefulness, however, by the fact that it operates as described only at a single frequency. Furthermore, the magnitude of the inverted impedance can be varied only by altering the physical dimensions of the line or reactance network. Also the power input to the inverted impedance is necessarily always equal to the power delivered to the terminal impedance, since the line neither furnishes nor absorbs power.

In contrast to the limitations of known impedance inverting arrangements, the present invention provides a means for impedance inversion which operates independently of frequency and which permits control of the magnitude of the inverted impedance without physical alteration of circuit elements and also provides for independent control of the amount of power delivered to the impedance which is being inverted, as compared with the amount of power delivered to the points presenting the inverse impedance.

In the accompanying drawing:

Fig. 1 shows an impedance inverting device, Fig. 2 shows an impedance inverting device arranged to provide an impedance which is inverse to a given impedance,

Fig. 3 shows an impedance inverting device inserted in a filter for providing uniform gain.

Referring specifically to Fig. 1, reference numeral 1 represents a screen grid amplifier tube

having its plate and grid circuits energized with suitable direct operating voltages by way of choke 2 and impedance 3 respectively and having its screen circuit connected to a suitable positive potential as indicated by the plus sign adjacent the lead to screen 4. The source 12 of grid energizing potential is preferably adjustable. The cathode of tube 1 is connected to a line 5 whose terminal 6 acts as one input terminal for the impedance inverting circuit, while its terminal 7 acts as one output terminal for the device. Condensers 8 are blocking condensers. The other alternating current input terminal is denoted by numeral 9 and the other alternating output terminal by numeral 10. So far there has been described merely a conventional screen grid amplifier tube with means for separating its alternating input and output from its direct current energizing circuits. In accordance with the invention, however, a second screen grid tube 11, arranged to provide negative transconductance between its input electrode 15 and its output electrode 16, is connected with its alternating current input voltage derived from terminal 10, while its alternating output is connected to terminal 9. Its plate and grid circuits are energized in similar fashion to the plate and grid circuits of tube 1. In order that a negative transconductance may be obtained from screen grid tube 11, its screen 14 is maintained at a direct potential sufficiently higher than the direct potential of plate 16, so that due to secondary emission from plate 16 the current flow to plate 16 is reversed in direction but has a magnitude which is less the more negative the potential of input electrode 15. The potential of plate 16 is, therefore, adjusted to the value which produces a maximum of reversed current, so that the alternating plate circuit impedance is infinite or at least very high. The operation of an ordinary screen grid tube as a negative transconductance device is more fully described in U. S. Patent 2,093,781 granted to W. v. B. Roberts on September 21, 1937.

If the transconductance of tube 1 is represented by G_{12} and the absolute magnitude of the transconductance of tube 11 is represented by G_{21} , then a positive increment of potential impressed upon input terminal 9 causes an increment of current G_{12} to flow into the plate of tube 1, as indicated in direction by the arrow alongside the lead thereto. Similarly, a positive increment of potential at output terminal 10 causes a current to flow from plate 16 of tube 11 out through the input circuit connected be-

5 between terminals 6 and 9 as indicated by the arrow above terminal 9. Thus the apparent impedance between input terminals 6 and 9, that is the ratio of the voltage applied thereto to the current flowing therebetween in response to said voltage depends upon the load impedance connected between terminals 10 and 7 across which voltage is developed by the plate current of tube 1.

10 Assuming an impedance Z connected between terminals 10 and 7, it will be seen that the potential developed at terminal 10, per volt applied to terminal 9, is equal to $-ZG_{12}$. As a result of this potential being applied to input electrode 15 15 of tube 11 a current flows from terminal 6 up through the input circuit to terminal 9 and thence, in the opposite direction to the arrow adjacent terminal 9, into the plate 16. The magnitude of this current is $ZG_{12}G_{21}$. Hence the 20 apparent input impedance between terminals 6 and 9 is

$$\frac{1}{ZG_{12}G_{21}}$$

25 which impedance is by definition inverse to impedance Z .

Referring now to Fig. 2, the rectangle marked TWT represents any device having the properties of the combination of tubes shown in Fig. 1. Since the arrangement shown in Fig. 1 is such that voltage impressed upon the input terminals determines the current flow between the output terminals, and vice versa, the arrangement as a whole will hereinafter be referred to as a two-way transconductance device, or for the sake of brevity, TWT. As was explained in connection with Fig. 1, the input impedance measured between terminals 6 and 9 of Fig. 2 is

$$\frac{1}{ZG_{12}G_{21}}$$

40 This impedance is inverse to the output impedance Z and its magnitude depends upon the product of the two transconductances G_{12} and G_{21} . Hence since it is well known that the transconductance of each of the tubes of Fig. 1 may be varied by varying the bias potential of its grid, the magnitude of the inverse impedance obtained between terminals 6 and 9 of Fig. 2 can be controlled by a mere variation of electrical potentials, thus permitting various types of automatic control which would not be feasible in case it were necessary to vary the physical dimensions of circuit components.

45 The application of the arrangement of Fig. 2 to a few representative problems will now be discussed. Let us suppose that the output impedance Z consists of a pure inductance L . Then the apparent input impedance at terminals 6 and 9 will be that of a condenser whose capacity is $G_{12}G_{21}L$. The magnitude of this effective capacity between terminals 6 and 9, however, may be adjusted by varying the product $G_{12}G_{21}$. Similarly, if Z consists of a capacity C then the inverse impedance obtained between terminals 6 and 9 will be that of an inductance whose value is

$$\frac{C}{G_{12}G_{21}}$$

50 and is similarly controllable.

55 If the transconductances of both devices of Fig. 1 should have the same sign, however, a change of sign occurs along with impedance inversion. The transconductances of the two devices 1 and 11 of Fig. 1 can be given the same sign by changing the screen and plate supply

voltages of either to the same values as employed in the other. Thus an inductance L between output terminals 7 and 10 becomes a positive reactance between terminals 6 and 9, but this positive reactance decreases with increasing frequency so that it is at all frequencies equal and opposite to the reactance of a capacity $G_{12}G_{21}L$. Similarly, a condenser between 10 terminals 7 and 10 provides a negative reactance between terminals 6 and 9 whose magnitude increases directly with frequency and hence is equal and opposite at all frequencies to the reactance of a certain inductance. It will thus be seen that a universal resonance, i. e., equality and opposition of signs at all frequencies, can be obtained between a given capacity and the input terminals of a TWT terminated by an inductance, if the TWT is composed of transconductances of similar sign. The same remarks apply to universal resonance with a given inductance element. This phenomenon of universal resonance has many possible applications, including resonant voltage rise independent of frequency for "untuned" amplifiers, and the wiping out of undesired susceptance in parallel with resistance coupling of a wide band amplifier. This last result is of course accomplished by simply connecting the input terminals, such as 6 and 9 of Fig. 2, across the undesired capacity, and connecting across the output terminals 7 and 10 an inductance equal to the undesired capacity divided by the product of the transconductances of the TWT.

20 Referring now to what will be called the normal construction of the TWT (that is, with transconductances of opposite signs) it will be demonstrated that the TWT device may be used to match any two impedances which are inverse to each other. Fig. 3 shows an example of this application.

25 In Fig. 3 the TWT device is shown inserted in a filter of the so-called constant k type. This type of filter is composed of series elements Z_1 and shunt elements Z_2 whose product is independent of frequency. In the drawing the filter is shown as extending indefinitely both to right and left as the number of sections employed has no relation to the present invention. In accordance with the invention, and as indicated by the impedance values attached to the various elements, the right hand portion of the filter is 30 terminated at mid-shunt where it is connected to the output terminals 7 and 10 of the TWT. Hence the impedance to which terminals 7 and 10 are connected is equal to

$$\sqrt{Z_1Z_2} \div \sqrt{1 + \frac{1}{4} \frac{Z_1}{Z_2}}$$

35 The inverted impedance measured between terminals 6 and 9 in the absence of the left hand portion of the filter is then

$$\frac{\sqrt{1 + \frac{1}{4} \frac{Z_1}{Z_2}}}{G_{12}G_{21}\sqrt{Z_1Z_2}}$$

40 Now further, in accordance with the invention, the value $G_{12}G_{21}$ is adjusted to be equal to

$$\frac{1}{Z_1Z_2}$$

45 whereby the input impedance between terminals 6 and 9 becomes

$$\sqrt{Z_1Z_2} \sqrt{1 + \frac{1}{4} \frac{Z_1}{Z_2}}$$

50 But this last expression is exactly the impedance of the filter when terminated at mid-series.

Therefore an exact impedance matching between the left hand filter portion and the TWT is obtainable by terminating the left hand portion of the filter at mid-series as indicated on the drawing. Since the TWT device operates as an impedance inverter in both directions, transmission may be effected in either direction through the system without reflection losses at the TWT, the only difference between the two directions of transmission being in the amount of power gain that occurs in traversing the TWT. An improvement is thus effected over the prior art of terminating a filter with a simple resistance that is not a perfect termination at all frequencies in order to insert an amplifying device for producing gain.

The power gain occurring in passing through a TWT device is calculated as follows: voltage e impressed between terminals 6 and 9 of Fig. 2, for example, produces a current $eG_{12}G_{21}Z$ between these terminals, but at the same time causes a current eG_{12} to flow between terminals 7 and 10. The voltage drop across Z is therefore $eG_{12}Z$ and the power developed in impedance Z is $e^2G^2_{12}Z$. The ratio of this power to the input power $e^2G_{12}G_{21}Z$ is

$$\frac{G_{12}}{G_{21}}$$

Now in Fig. 3 the product $G_{12}G_{21}$ has been fixed by considerations already discussed, but the power gain

$$\frac{G_{12}}{G_{21}}$$

may be adjusted by varying both G_{12} and G_{21} in such a way that their product is not altered. Hence, in fine, Fig. 3 shows how a variable gain may be inserted in a filter without introducing any mismatching or reflection losses.

It will be understood that while a particular form of construction has been discussed for a TWT device, many other forms may be used for producing the same results. For example, a single electronic device having two sets of electrodes each arranged to have transconductance with respect to the other set could be used. Furthermore, it is not necessary that either of

the component transconductance devices have a negative transconductance inherently, as the effect of a negative transconductance may be obtained by a suitable reversing transformer or its equivalent. I therefore do not consider my invention to be limited to the particular construction of the TWT device shown herewith, but only in accordance with the following claims.

What I claim is:

1. Means for producing between a first pair of terminals an apparent alternating current impedance which is inverse to a given impedance connected between a second pair of terminals, comprising in combination a one way positive transconductance device having input electrodes connected to one of said pairs of terminals and output electrodes connected to the other of said pairs of terminals, and a one way negative transconductance device having input electrodes connected to that pair of terminals to which the output electrodes of said positive transconductance device are connected, and having output electrodes connected to that pair of terminals to which the input electrodes of said positive transconductance device are connected. 25

2. The combination defined in claim 1 wherein means are included for controlling the transconductance of one of said devices whereby to control the magnitude of said apparent impedance. 30

3. The combination defined in claim 1 wherein said given impedance consists of a wave filter having one kind of termination whereby said apparent impedance is proportional to the impedance of a hypothetical second and similar 35 wave filter having an alternative kind of termination, and wherein there are provided means for controlling the product of the transconductances of said devices to render said apparent impedance equal to the impedance of said second filter, and means for controlling the ratio of the transconductances of said devices whereby to control the power gain between said apparent impedance and said given impedance, said kinds of terminations being mid-series and mid- 40 shunt terminations. 45

WALTER VAN B. ROBERTS.
